UNITED STATES PATENT OFFICE.

ELIZABETH MILES, OF EVANSTON, ILLINOIS.

MATERNITY-GOWN.

1,104,437.

Specification of Letters Patent. Patented July 21, 1914.

Application filed December 1, 1913. Serial No. 803,903.

To all whom it may concern:

Be it known that I, ELIZABETH MILES, a citizen of the United States, and a resident of the city of Evanston, county of Cook, 5 and State of Illinois, have invented certain new and useful Improvements in Maternity-Gowns, of which the following is a specification.

My invention relates to improvements in 10 maternity skirts and has for its object the production of a skirt of this character which will be of neat and finished appearance and which when expanded or circumferentially adjusted will retain its shape so that the alteration or variation in the size thereof will 15 be unnoticed.

A further object is the production of a 20 skirt which will be of simple and economical construction, one which may be readily and easily expanded or circumferentially 25 adjusted, and one which will be efficient in use.

Other objects will appear hereinafter.

The invention consists in the combinations 25 and arrangements of parts hereinafter described and claimed.

The invention will be best understood by reference to the accompanying drawing forming a part of this specification, and in 30 which—

Figure 1 is a perspective view of a skirt embodying my invention, and Fig. 2 is a top plan view thereof.

The preferred form of construction as 35 illustrated in the drawing comprises a skirt, the body of which is formed of two similar pieces of fabric 1 and 2 which form the front and rear respectively of the skirt. Said members 1 and 2 are connected together by lines of stitching 3, the seams formed being positioned at the sides of the skirt, and the adjoining edges being so cut or formed as to result in a skirt which will 40 be adapted to snugly fit the hips of the wearer as clearly shown in Fig. 1.

Provided centrally at the front and rear sides of the skirt are panels 4 and 5 which are defined by lines of stitching 6 and 7 respectively, said lines of stitching extending 50 parallel with and being slightly spaced from the longitudinal edges of the panels so as to result in the formation of tucks at said panel edges. Formed at the longitudinal edges of said panels 4 and 5 are loose inwardly turned plaits or folds 8 and 9 respectively, adapted to be adjusted, that is

let out or taken in to increase or decrease the size of the fold so as to allow for expansion or circumferential adjustment of the skirt as desired.

The garment is held snugly about the body of the wearer by means of longitudinally adjustable straps 10 provided at the upper edge of the skirt, there being one strap 10 provided at each side of the skirt 65 connecting the tucks or longitudinal edges of the panels 4 and 5 at the corresponding side of the skirt. With this arrangement it will be seen that the panels 4 and 5 will be drawn snugly and tightly about the body 70 of the wearer, the portions of the skirt intermediate said panels being free to adjust themselves according to the space intervening 75 the adjacent edges of said panels and which space, as will be observed, is determined by the straps 10. With this arrangement then, it will be seen that in the use of the skirt, expansion or circumferential adjustment thereof is effected by simply adjusting the straps 10, the folds or plaits 8 and 9 adjusting themselves to correspond with the adjustment of said straps. The pressure of the straps and the longitudinal edges of the panels upon said plaits 8 and 9 will serve to hold the latter in position, it 80 having been found through usage that it is 85 unnecessary to employ additional fastening means for this purpose.

A belt 12 is provided which is secured at 13 to the upper edge of the panel 5, the free 90 ends of said belt being provided with co-operating ball and socket fastenings 14 for securing the belt about the wearer, there being a plurality of said ball and socket fastenings in order to permit expansion of the 95 belt to correspond with the adjustment of the skirt. The belt 12 is adapted when in position to hide the straps 10 and the same is sufficiently wide to permit slight raising or lowering of the waist line of the skirt 100 without exposing the upper edge of the skirt above or below the same, such raising or lowering of the waist line of the skirt resulting through alteration in the form of the wearer during development when the 105 skirt is in use.

At one edge of the rear panel 5 is provided a slit 15 which forms a placket opening, ball and socket fastening 16 being provided to releasably lock said opening during use 110 of the skirt.

A skirt of the construction set forth is

simple and economical in construction and by reason of the arrangement of the panels and the adjustable connection between the same the form of the skirt, when worn, remains unchanged and alteration in the circumference thereof is rendered unnoticeable. The greatest expansion in the skirt occurring at the waist line, the plaits or folds 8 and 9 taper toward their lower ends as 10 shown.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 20 the appended claims.

Having described my invention what I claim as new and desire to secure by Letters Patent is:

1. A skirt comprising a body having longitudinally extending panels provided at the front and rear sides thereof; inwardly turned adjustable plaits provided at the longitudinal edges of said panels whereby the circumference of the skirt may be varied 25 by adjusting said plaits; and longitudinally adjustable straps extending between and connecting the upper end portions of the longitudinal edges of the front and rear panels at corresponding sides of the skirt for 30 determining the circumference of the skirt and indirectly holding said plaits in positions of adjustment, substantially as described.

2. A skirt comprising a body having longitudinally extending panels provided at the front and rear sides thereof; inwardly turned adjustable plaits provided at the longitudinal edges of said panels whereby the circumference of the skirt may be varied by 40 adjusting said plaits; longitudinally adjustable straps extending between and connect-

ing the upper end portions of the longitudinal edges of the front and rear panels at corresponding sides of the skirt for determining the circumference of the skirt and 50 indirectly holding said plaits in positions of adjustment; and an expansible belt provided at the waist of said skirt connected therewith intermediate its ends with one of 55 said panels, substantially as described.

3. A skirt comprising a body formed of two similar pieces of fabric joined together so that the seams thereof are positioned at the sides of the skirt; a panel formed centrally in each of said pieces defined by longitudinally extending lines of stitching which form tucks at the longitudinal edges of said panels; loose inwardly turned adjustable plaits provided at and coextensive with said tucks; and longitudinally adjustable members extending between and connecting the upper end portions of the tucks of the front and rear panels at corresponding sides of the skirt, substantially as described. 70

4. A skirt comprising a body having longitudinally extending panels provided at the front and rear sides thereof; inwardly turned adjustable plaits provided at the longitudinal edges of said panels whereby the circumference of the skirt may be varied by adjusting said plaits; loops secured to the longitudinal edges of said front panels; straps, each having its rear end secured to a vertical edge of said rear panel, 75 extending through one of said loops and its other end adjustably secured upon itself; and a belt secured to said rear panel and extending over said straps hiding the latter from view, substantially as described. 80 85

In testimony whereof I have signed my name to this specification in the presence of two subscribing witnesses.

ELIZABETH MILES.
